(57) **CLAIM**

The ornamental design for a key ring with illuminatable pendant, as shown.

DESCRIPTION

FIG. 1 is a front perspective view of a key ring with illuminatable pendant showing my new design;

FIG. 2 is a front, right-side, bottom perspective view thereof;

FIG. 3 is a rear, right-side, bottom perspective view thereof;

FIG. 4 is a front-elevational view thereof;

FIG. 5 is a right-side elevational view thereof;

FIG. 6 is a left-side elevational view thereof;

FIG. 7 is a rear view thereof;

FIG. 8 is a bottom view thereof;

FIG. 9 is a top view thereof;

FIG. 10 is a front, left-side bottom perspective view of a second embodiment thereof;

FIG. 11 is a front, right-side, bottom perspective thereof;

FIG. 12 is a rear, left-side, bottom perspective view thereof;

FIG. 13 is front view thereof;

FIG. 14 is a right-side elevational view thereof;

FIG. 15 is a left-side elevational view thereof;

FIG. 16 is a rear view thereof;

FIG. 17 is a bottom view thereof; and,

FIG. 18 is a top view thereof.
